Primary Examiner — Gino Colan*(74) Attorney, Agent, or Firm* — Cramer Patent & Design, PLLC(57) **CLAIM**

The ornamental design for a valve, as shown and described.

DESCRIPTION

FIG. 1 is a top front right perspective view of a valve showing my new design;

FIG. 2 is a top rear left perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines shown in the figures are for the purpose of illustrating proportions of the valve and form no part of the claimed design.
